JOHN REID SUTTON, OF BROOKLYN, NEW YORK.

Letters Patent No. 99,370, dated February 1, 1870.

RAMMER FOR PACKING TOBACCO.

The Schedule referred to in these Letters Patent and making part of the same.

To all whom it may concern:

Be it known that I, JOHN REID SUTTON, of Brooklyn, in the county of Kings, and State of New York, have invented a new and useful Improvement in Rammers for Packing Tobacco; and I do hereby declare that the following is a full, clear, and exact description thereof, which will enable others skilled in the art to make and use the same, reference being had to the accompanying drawings, forming part of this specification.

This invention relates to improvements in the small rammers used by tobacco-packers for packing the fine tobacco into the small papers in which it is packed for retail purposes; and

It consists in the application, to the end of the rammer which acts on the tobacco, of a projection resembling in form, to some extent, the bowl of a pipe.

Also, in the application to the rammer, and for action in conjunction therewith, of a sliding pin or punch, for forcing down into the tobacco, to make a hole for the stem of a pipe, in such relation to the recess formed by the said projection, that when the rammer is withdrawn, and before the paper is withdrawn, a smoking-pipe can be conveniently packed in the paper with the tobacco.

Figure 1 represents a side elevation of my improved rammer, and

Figure 2 represents an elevation of the same, and a sectional elevation of the packing-cases with which it is used, showing the tobacco packed therein.

Similar letters of reference indicate corresponding parts.

A and B are the moulds or packing-cases commonly used for packing the tobacco into the small papers in which it is sold to consumers, and

C represents the paper for the reception of the tobacco, and which is first folded around the lower part of the funnel-mouthed case B, and inserted in the case

A, to be held in a vertical position for the reception of the tobacco placed in the funnel-mouthed case B, and forced down to the top of A by the rammer, after which the rammer and the case B are withdrawn, leaving the paper in case A to be folded at the top and withdrawn.

My invention consists in the application, to the rammer D, of the projection E, and the sliding punch F, for forming a space in the top of the tobacco for the bowl of a pipe, and a hole therefrom to the bottom for the stem, to enable me to pack a smoking-pipe in the paper with the tobacco, with facility, and to fold the paper over it, and make a neat package of the same size as those without the pipes.

In operation, the rammer is first forced down as far as required to pack the tobacco, with the punch remaining up, then the punch is forced down.

The projection E may be formed on the end of the rammer in any suitable way, and the punch F is preferably arranged to rise up through a hole in the square part of the rammer, and to connect with a sleeve, G, capable of sliding up and down on the shank. Any other approved arrangement thereof may, however, be made.

Having thus described my invention,

I claim as new, and desire to secure by Letters Patent—

1. The combination, with the rammer D, of the projection E and punch F, arranged for operation substantially as specified.

2. The combination of the rammer, punch, and sleeve, all substantially as specified.

The above specification of my invention signed by me, this 21st day of December, 1869.

JNO. REID SUTTON.
